UNITED STATES PATENT OFFICE.

GEORGE W. WALKER, OF FAR ROCKAWAY, NEW YORK.

MECHANICAL TOY HORSE.

1,337,300.

Specification of Letters Patent. Patented Apr. 20, 1920.

Application filed August 22, 1919. Serial No. 319,270.

To all whom it may concern:

Be it known that I, GEORGE W. WALKER, a citizen of the United States, residing at Far Rockaway, in the county of Queens and 5 State of New York, have invented certain new and useful Improvements in Mechanical Toy Horses, of which the following is a specification.

This invention relates to toy vehicles and 10 more particularly to a vehicle which may be propelled by rocking the body when seated on the vehicle.

The primary object of the invention is to provide an apparatus of this character 15 which may be especially used by children and which will afford exercise and amusement.

One of the objects of the invention is to provide a vehicle of this character which 20 will have the body portion thereof, shaped or designed to simulate an animal and which may be mounted by the user and rocked backwardly and forwardly for imparting movement to the apparatus in order that it 25 will be propelled.

The above and additional objects are accomplished by such means as are illustrated in the preferred embodiment and in the accompanying drawings, wherein like characters 30 denote like or corresponding parts throughout the several views, in which:—

Figure 1 is a side elevation, partly in section, of the device constructed in accordance with my invention.

Fig. 2 is a rear end elevation thereof.

Fig. 3 is a plan view of the operating mechanism and supporting frame.

Fig. 4 is a section taken approximately on the line 4—4 of Fig. 3.

Fig. 5 is a section taken on the line 5—5 of Fig. 1, and

Fig. 6 is a section taken on the line 6—6 of Fig. 1.

Figs. 7 and 8 are detail sections of portions of the structure forming the supporting frame for the axles.

Referring to the drawings, wherein is illustrated the preferred form of my invention, and in which like characters of reference indicate like or corresponding parts throughout the several views, the front wheels 1 and 2 are mounted upon the ends of the front axle 3 and the latter is provided with an offset portion 4 to form a crank shaft, the crank including the radial portions 5 and the straight portion 6. The rear

wheels 7 and 8 are attached to the rear axle 9 at the ends thereof and this axle is also shaped to provide a crank shaft 10 comprising the radial portions 11 and the straight 60 portion 12.

The carriage or body of the vehicle is designed and shaped to simulate an animal and as shown in the drawing, the shape is in the general outline of a horse. This body 65 consists of the main portion 13, having a seat 14 mounted thereon. The forward end of the portion 13 has pivoted thereto the head 15 which is provided with laterally projecting handle bars 16. The front portion of the body is provided on its interior with a king pin 17 glued and bolted in the body and having its upper end projecting into the head 15 as indicated at 18.

The portion 20 indicates the front legs of 75 the animal and this portion is pivoted on the projection 21 of the king pin 17 and is provided with the foot rest 22 upon which the feet of the user may rest while the device is in use. The lower end of the portion 20 is 80 connected to the straight portion 6 of the crank shaft at the forward end as shown to advantage in Figs. 3 and 4. A recess 23 is provided in the portion 20 to receive the straight portion 6 and the latter is held 85 against displacement by a removable plate 24 and it will be obvious that the straight portion 6 may be attached to the front leg portion 20 in any preferred manner. Wear- 90 plates 25 are provided between the portion 20 and the crank portion 5 of the front shaft.

The portion 26 at the rear of the body forms the rear legs for the animal and these are held in position by a dowel pin 27 the 95 ends of which are projected into recesses formed in the members 13 and 26 as shown in Fig. 1. This portion 26 is mounted on the rear axle and is provided for this purpose with a transverse recess 28 which receives 100 the straight portion 12 of the crank shaft and the latter is held against displacement from the depression 28 by the removable plate 29. Wear plates 30 are arranged between the portion 26 and the radial portions 105 11 of the crank shaft as shown.

The frame is supported on the front and rear axles and comprises side bars 31 arranged in parallel relation and having their rear ends connected to the rear axle and 110 their front ends provided with extensions 32 across which the ends of the front axle

are extended. The body of the animal is supported by this frame and consequently the frame is equipped with a supporting device which consists of the struts 33 attached to the side bars 31 and joined together at their upper ends beneath the body 13 and pivotally connected to the latter by means of an attaching plate 33' carrying a pivot bolt 34. In this manner the body will be permitted to rock so that the front and rear ends will be alternately raised and lowered for imparting movement to the crank shaft. A brace member 35 is also provided which has one end secured to a brace rod 36 the ends of which are joined to the side bars 31 and the opposite end of the member 35 is attached to a transverse plate 37 the intermediate portion of the member 35 being shaped to form a yoke member substantially U-shaped in construction as shown to advantage in Fig. 1 whereby the parts 32 will be more effectively braced. The end of the member 37 has attached thereto the forwardly projecting bar 38 which is fastened, as indicated at 39 to the connecting bar 40 which is bent upwardly and is connected to the straight end portions 32.

The two rear wheels are mounted on the ends of the rear axle and each wheel is provided with a circular plate 42 rigidly secured to the exterior surface of the wheel as shown. Each end of the axle has a rectangular extension 43 which is projected through a rectangular opening in the corresponding plate 42 in order that the wheel will turn with the axle. One end of the front axle is constructed in the same manner, being provided with a squared portion 44 projected through a rectangular opening in the plate 45 which is secured to the front wheel 1. The other front wheel 2 is provided with a plate 46, but this plate has a circular opening and the corresponding end 45 of the axle 3 is provided with a straight, instead of a square end, which is projected through the circular opening in order that the wheel 2 may rotate independently of the axle. In use, the seat 14 will be occupied by the user and the foot rest will support the user's feet. The body will then be rocked backwardly and forwardly to swing on the pivot member 34 so that the front and rear ends will be alternately raised and lowered. In this manner a rotary movement

will be imparted to the crank shaft and since the recessed slot 28 will permit free rotary movement of the rear crank shaft, it will be obvious that the rear end will be alternately raised and lowered, while the recess 23 will permit free rotary movement of the front crank shaft, the front end will also be alternately raised and lowered and this alternate raising and lowering of the front and rear ends will cause the axle to be rotated whereby movement will be imparted to the wheels to propel the vehicle.

The foregoing description and accompanying drawings have reference to what might be considered to be the approved or preferred form of my invention. I desire it to be understood that I may make such changes in the construction, combination and arrangement of parts, materials, dimensions, et cetera, as may prove expedient and fall within the scope of the appended claims.

Having thus fully described my invention what I claim as new and desire to secure by Letters Patent, is:—

1. In a device of the class described, the combination of a wheel supported frame, crank shafts mounted on said frame and connected to said wheels, a body pivotally supported above the frame intermediate the ends thereof, depending extensions provided at each extremity of the body, a U-shaped plate attached to the terminals of said extensions so as to form transverse recesses to receive said crank shafts.

2. In a device of the class described, the combination of a frame, wheels for supporting said frame, crank shafts mounted on said frame and having rectangular terminals, disks carried by said wheels and having rectangular openings for receiving the terminals of said crank shafts, a body pivotally supported above the frame intermediate the ends thereof, depending extensions provided at each extremity of the body, a U-shaped plate attached to the terminals of said extensions so as to form transverse recesses to receive said crank shafts.

In testimony whereof I affix my signature in presence of two witnesses.

GEORGE W. WALKER.
